Louis Meyers
Inventor:

UNITED STATES PATENT OFFICE.

LOUIS MEYERS, OF BROOKLYN, NEW YORK.

LOCK.

1,274,181.

Specification of Letters Patent. Patented July 30, 1918.

Application filed April 23, 1915. Serial No. 23,307.

To all whom it may concern:

Be it known that I, LOUIS MEYERS, a citizen of the United States, residing at Brooklyn, in the county of Kings and State of New York, have invented certain new and useful Improvements in Locks, of which the following is a specification.

This invention relates to improvements in closures for doors, particularly sliding doors such as are used in connection with elevators in buildings.

One of the objects of the invention is to provide a closure of the kind referred to, comprising a fixed abutment, a rod having one end detachably connected with the fixed abutment, and a member carried by the sliding door having a rotatable part which when turned to one position provides a passage through which the rod may be passed longitudinally, and which, when turned to another position, blocks such movement of the rod; the said rotatable part being preferably key-and-manually operated.

Other objects and aims of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are to be taken as a part of this specification, and in which I have shown one of the various possible embodiments of this invention as at present preferred:

Figure 1 is a perspective view, illustrating the application of my invention to an ordinary form of elevator door;

Fig. 2 is a front elevation, with parts in section and parts broken away, illustrating the invention and its application;

Fig. 3 is a sectional view, taken on the line 3-3 of Fig. 2;

Fig. 4 is a sectional view, taken on the line 4-4 of Fig. 2;

Fig. 5 is a detail view with parts in section, illustrating the detachable connection of the rod with the fixed abutment;

Fig. 6 is a plan view of a modified form of the pinion 30; and

Fig. 7 is a similar view of a modified form of cylinder 18 cooperating with such pinion 30.

In the drawings, there is shown at 6 one of the doors controlling access to an elevator shaft. This door may be pivoted in the usual way, so that it can be swung out when necessary, although ordinarily it remains in the position shown in Fig. 1. The numeral 7 indicates another door, which is slideable with relation to the door 6, and the purpose of my invention, in the form illustrated, is to provide means for holding the door 7 in the Fig. 1 position when desired, and for permitting it to slide relatively to the door 6 when necessary or desirable.

To this end, I may provide upon the edge 70 of the door 6, which, by the way, in the present form of embodiment, is in a plane outside that of the door 7, a fixed abutment member which comprises a supporting plate 8 having a socket piece 9, provided with a flared mouth 10, which socket member 9 is intended to receive one end of a locking rod 11. Preferably the socket member 9 is interiorly provided with a projection 12, which is intended to back into an annular groove 14 cut into the end of the rod 11. When the rod 11 has been inserted into the socket member 9, it is held with its groove 14 in engagement with the projection 12, as by means of a presser 15 normally urged toward the rod by means of a coiled spring 16 surrounding an operating rod 17 which protrudes through the wall of the socket member 9 as shown in Fig. 2. The other end of the rod 11 passes through a cylinder 18 90 which is rotatably supported in a casing 19. This casing 19 comprises a front plate 20, a rear plate 21, the latter being secured to the door 7, and both plates being interiorly cut out to receive the cylinder 18. The cylinder 95 has a stem 22 which projects through the front plate and on this stem there is a knob 24 by which it may be turned. The cylinder has a diametrical bore 25 adapted to snugly receive the rod 11. It will be evident that 100 when the cylinder is turned to position with its bore in line with the rod 11, the rod 11 may be slid through it, and when the cylinder is in the position shown in Fig. 2, slideable movement of the rod through the cylinder is prevented. The cylinder has on its periphery a stop pin 26, which makes contact with suitable stops formed on the inside of the front plate 20, so that the turning movement of the cylinder is limited to a 110 quarter of a revolution.

Preferably also there is a coiled spring

27 surrounding the stem 22 and bearing between the cylinder and the front plate 20, the said spring urging the cylinder toward the rear plate of the casing. The rear plate of the casing is provided with an aperture through which extends a squared shaft 28. The end of this shaft 28 within the casing carries a pinion 29 that meshes with a pinion 30 secured to the rear face of the cylinder 18, so that rotation of the pinion 29 will cause rotation of the cylinder 18. The rotation of this squared shaft 29 is controlled as by means of a usual cylinder lock 32, which is properly positioned in the door 7, with its key-hole on the opposite side of the door from that occupied by the knob 24. A screw 31 may be employed to hold the pinion 29 upon the shaft 28.

It will be understood that the front and rear plates making up the casing 19 are cut out at the sides, as shown in Fig. 4, in line with the bore of the cylinder 18 when the cylinder is turned to a position in which the axis of the bore will be parallel with the axis of the rod 11. Consequently it will be evident, referring to Fig. 2, that if the cylinder 18 be turned either by means of the knob 24 or by the use of a key, so as to bring the bore of the cylinder in line with the axis of the rod 11, the door 7 may be slid back, the rod 11 simply sliding through the cylinder and the casing.

When it is desired to lock the door 7, the cylinder is turned either by means of the knob 24 or by the use of a key, to the position indicated in Fig. 2, so that the rod 11 cannot be moved lengthwise through the casing and the cylinder. If it is desired to remove the rod 11 entirely, the cylinder is turned so that the rod may slide relatively to the cylinder and the casing, and is pushed to the left (Figs. 1 and 2) sufficiently to clear the socket member 9, the presser 15 being of course raised so as to permit the rod to be lifted out of engagement with the projection 12.

The operation and use of this closure are believed to be almost self-evident from the description and disclosure, and need not be further referred to. It may be said, however, that so far as the application of the invention is concerned, it would make no difference whether the so-called "fixed abutment", meaning the socket member 9, or its equivalent, were placed on the door 6 or on the door 7; or of course I might have but a single door slidably relatively to the door casing, and it would make no difference whether the door casing or the door, carried the fixed abutment, or which carried the locking cylinder.

In the form shown in Fig. 1, the knob 24 for controlling the cylinder, is supposed to be upon that side of the door 7 which faces into the room or apartment, while the cylinder lock 32 is on the opposite side of the door, that is, upon that side of the door which faces the elevator shaft.

It will be evident that the device may readily be brought from unlocked to locked position from the inside of a room by pulling on the knob 24, resulting in the disengagement of the two pinions 29 and 30, whereupon the cylinder 18 may be turned to locking position, and then the knob 24 released and the spring 27 permitted to urge the pinion 30 back into engagement with the pinion 29. Instead of having the pinion 30 carried by or integral with the cylinder 18, I may provide a pinion 30, as shown in Fig. 6, pivoted to the back wall of the casing in fixed position, the said pinion being provided with a number of holes 33. The opposed face of the cylinder 18, as shown in Fig. 7, will be provided with studs 34 adapted to register with the holes 33. Accordingly, when it is desired to turn the cylinder from the inside of a room, this is readily accomplished by pulling on the knob 24, whereupon the cylinder moves away from the pinion 30, after which the cylinder may be turned a quarter of a revolution and then allowed to spring back, when the studs 34 will again engage with the holes 33.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, might be said to fall therebetween.

I claim:

1. A closure of the kind described, comprising a fixed socket member, a rod having one end detachably connected with the socket member, and a casing provided with a bore throughout its length, said casing having a rotatable member arranged therein and provided with a bore which when turned to one position provides a passage through said bores through which the rod is adapted to slide and which when turned to another position blocks such movement of the rod.

2. A closure of the kind described, comprising a fixed socket member, a rod having one end detachably connected with the socket member, a casing provided with a bore throughout its length, said casing having a rotatable member arranged therein and provided with a bore which when

- turned to one position provides a passage through said bores through which the rod is adapted to slide and which when turned to another position blocks such movement of the rod, and rotatable key-operated means for controlling the rotation of such rotatable member.
3. In a device of the kind described, a casing having alined openings in its walls, a cylinder bodily movable and rotatably mounted within the casing and having a diametrical bore adapted when moved in one position to be brought into alinement with said openings and when moved in another position to block said openings, and pinion means engageable with the cylinder for rotating the cylinder.
4. In a device of the kind described, a casing having alined openings in its walls, a cylinder bodily movable and rotatably mounted within the casing and having a diametrical bore adapted when moved in one position to be brought into alinement with said openings and when moved in another position to block said openings, and key operated pinion means engageable with the cylinder for rotating the cylinder.
5. In a device of the kind described, a casing having alined openings, a bodily and rotatably movable member within the cas-
- ing and having a bore adapted to be brought into line with the openings in the casing, whereby a passageway is provided through the casing and rotatable member, and means for moving said member so as to bring its bore into and out of line with said openings as desired.
6. In a device of the kind described, a casing having alined openings in its walls, a rod adapted to pass through said openings, and bodily and rotatably movable means within said casing adapted to prevent or permit as desired the passage of such rod through the openings.
7. In a device of the kind described, a casing, a bodily and rotatably movable cylindrical locking member, within the casing, a pinion rotatable with the cylinder, a second pinion meshing with the first, means for maintaining such pinions in engagement, and means for disengaging them.
8. In a device of the kind described, a casing, a bodily and rotatably movable cylindrical locking member within the casing, and a pinion, said cylindrical member and the pinion having interengaging portions whereby they may be engaged or disengaged with each other.

In testimony whereof I affix my signature.
LOUIS MEYERS.
